UNITED STATES PATENT OFFICE.

OAKLEY S. WALKER, OF WORCESTER, MASSACHUSETTS.

ELECTRICAL SWITCH.

1,031,031.

Specification of Letters Patent.

Patented July 2, 1912.

Application filed November 30, 1909. Serial No. 530,533.

To all whom it may concern:

Be it known that I, OAKLEY S. WALKER, a citizen of the United States, residing at Worcester, in the county of Worcester and 5 Commonwealth of Massachusetts, have invented a new and useful Improvement in Electrical Switches, of which the following is a specification, accompanied by drawings, forming a part of the same, in which—

10 Figure 1 is a plan view of an electrical switch embodying my present invention. Fig. 2 is a side elevation. Fig. 3 is an end view. Fig. 4 is a front view of a modified form. Fig. 5 is a side view of the same.

15 Fig. 6 is a detached view of the movable switch bar.

Similar reference characters refer to similar parts in the different figures.

The object of my present invention is to 20 provide an electrical switch adapted to be used in connection with the magnetized cores of a magnetic chuck, such as that described in Letters Patent of the United States No. 564,296, issued to me July 21, 25 1896.

The purpose of my present invention is to provide a switch which, by the ordinary movement of a switch bar, will enable the magnetic cores of a chuck to be energized 30 during the operation of the chuck and demagnetized immediately upon the termination of the chuck holding period to allow the work to be removed.

Referring to the accompanying drawings, 35 1 denotes a base plate upon which the switch is mounted. Near the center of the base plate are posts 2 and 3 in which a pair of switch bars 4 and 5 are pivoted, said bars being united at their free ends by a cross 40 bar 6 provided with a handle 7. The post 2 is connected with the positive pole of an electric circuit by means of a wire 8, and the post 3 is connected with the negative pole of the same electric circuit by a wire 9. 45 The pivoted switch bars 4 and 5 when thrown over into the position shown in Fig. 2 are brought into electrical contact with the posts 10 and 11. The posts 10 and 11 are electrically connected by wires 12 and 13 50 with the wiring of the magnetic chuck bringing the latter into the electric circuit through the positive wire 12 and the negative wire 13, causing an energizing of the cores of the chuck. If the switch bars 4 and 5 be raised out of contact with the posts 10 and 11, the electric circuit including the

magnetic cores of the chuck will be broken and the chuck will lose its magnetic power and allow the work to be removed therefrom. Sufficient residual magnetism, however, will remain to require force to remove the work which it is the object of my present invention to obviate. Upon the opposite end of the base 1 I mount the contact posts 14 and 15. The post 14 is adapted to contact with the switch bar 4 and the post 15 with the switch bar 5. The posts 14 and 15 are connected by the crossed wires 16 and 17, indicated by broken lines in Fig. 1, with the posts 10 and 11 respectively. If 70 the switch bars 4 and 5 be brought into contact with the posts 14 and 15 and allowed to remain, the electric current will be reversed, the wire 12 then becoming negative and the wire 13 positive through the connection of 75 the posts 10 and 11 with the posts 14 and 15 by means of the crossed wires 16 and 17. This operation of the electric switch bars 4 and 5, while it would accomplish the momentary demagnetization of the chuck 80 would result in the permanent magnetization of the chuck by an electric current moving in the reverse direction, causing the work to be as firmly held upon the chuck as before, and only permitting the work to be 85 removed during the momentary period of demagnetization. In the use of magnetic chucks it frequently happens that a large number of pieces are held upon the chuck at the same time, and while the momentary 90 demagnetization of the chuck might allow a single piece of work to be removed, if done quickly, and at the precise moment of demagnetization, the reenergizing of the chuck 95 would occur before all the pieces could be removed.

In order to prevent the reenergizing of the magnetic cores of the chuck by the reverse electric current I construct the posts 14 and 15 so that when the switch bars 4 and 5 are swung over from the position shown by solid lines to that shown by broken lines in Fig. 2, they will pass the contacting surfaces 18 of the posts 14 and 15 between the points 19 and 20, and enter the wide spaces between the base sections 21, 21 and out of contact with the posts 14 and 15. The speed of the movement of the switch bars 4 and 5, as most conveniently manipulated, being ascertained, the period of contact of the switch bars with the posts 14 and 15 will be determined by the length 105 110

of the contact surfaces 18. The length of the contact surfaces 18 is capable of adjustment by providing the contacting portion of the posts with sliding extension 5 pieces 22 held in place by clamping nuts 23.

The operation of my improved electric switch is as follows:—When a magnetic chuck electrically connected with the switch is to be brought into operation, the switch 10 bars 4 and 5 are moved into permanent contact with the posts 10 and 11, causing the energizing of the magnetic cores of the chuck by an electric current in which the wire 12 is positive and the wire 13 negative. When 15 the work is to be removed from the chuck the switch bars 4 and 5 are carried from the position shown in Figs. 1 and 2 to that indicated by the broken lines 5^a, Fig. 2, causing the switch bars to pass rapidly by the 20 contact surfaces 18 of the posts 14 and 15 and into the wide space between the bases 21 of the posts. During the contact of the switch bars 4 and 5 with the contact surfaces 18 the reversal of the electric current 25 is accomplished, the wire 12 becoming negative and the wire 13 positive. By adjusting the extension pieces 22 relatively to the speed at which the switch bars are moved the period of contact with the surfaces 18 30 may be determined, and the reversal of the current continued only so long as may be required to accomplish the complete demagnetization of the chuck.

In Figs. 4 to 6 inclusive, I have shown a 35 modification of my improved switch illustrating the application of my invention to a grinding machine comprising a stationary framework 24 and a movable member 25. A base plate 26 is attached to the stationary 40 framework 24 of the machine provided with contact surfaces 27 and 28, electrically connected by wires 29 and 30 with binding posts 31 and 32, the contact surface 27 being connected with the post 31 and the contact surface 28 being connected with the post 32. In alignment with the contact surfaces 27 and 28 are contact surfaces 33 and 34, the contact surface 33 being connected with the binding post 31 and the contact 45 surface 34 being connected with the binding post 32. From the binding posts 31 and 32 wires 35 and 36 lead to a magnetic chuck. Attached to the movable member 25 is a switch bar 37 supporting the cylindrical 50 chambers 38 and 39 containing the metal balls 40 and 41, which are held against the contracted outer ends of the chambers by means of spiral springs 42 and 43. The 55 balls 40 and 41 are electrically connected by wires 44 and 45 with a source of electricity, the ball 40 forming the positive pole and the ball 41 the negative. The movement of the 60 movable member 25 is preferably limited in one direction by a stop 46 and in the opposite direction by a stop 47, said stops being

so adjusted that when the member 25 is moved by hand against the stop 46 the balls 40 and 41 will be held in contact with the contact surfaces 27 and 28 forming an electrical communication with the chuck in 70 which the wire 35 is positive and the wire 36 negative. When the movable member 25 is moved in the opposite direction against the stop 47 the balls 40 and 41 will be moved entirely across and in contact with the contact surfaces 33 and 34 into the position shown in Fig. 4, in which each of the balls 40 and 41 are spaced from the contact surfaces 33 and 34.

During the period of contact of the balls 80 40 and 41 with the contact surfaces 33 and 34 the wire 35 is rendered negative, and the wire 36 positive through the connection between the contact surfaces 33 and 34 and the binding posts 31 and 32 by means of the 85 wires 48 and 49, thereby reversing the direction of the electric current. The contact surfaces 33 and 34 are each of the proper width relatively to the speed of the moving switch bar 37 to affect the demagnetization 90 of the magnetic cores of the chuck. Of course when the movable member 25 is mechanically moved by the operation of a machine so that its amplitude of movement is predetermined the stops 46 and 47 can be 95 omitted.

I am aware that it is not new to successively energize a magnetic core by a series of reversals of an electric current for the purpose of demagnetizing other articles which are brought into and gradually removed from the field of the magnetic core. 100

Devices of this class have been employed for the purpose of demagnetizing articles which had become magnetic, such as 105 watches, tools, etc. In all devices of this class, however, the object has not been to demagnetize the magnetic core but to successively energize it by means of a series of electric currents in opposite directions, 110 thereby reversing the polarity of the magnetic core, and utilizing its effect upon other articles for the purpose of demagnetizing them. The object of my present invention is not to demagnetize articles by gradually 115 bringing them into and gradually removing them from the field of a magnetic core whose polarity is successively reversed. The object of my present invention is to energize the magnetic cores of the chuck by a direct 120 current during a desired work holding period and then completely demagnetizing the chuck to allow the work to be removed.

I claim,

1. An electrical switch, comprising movable switch bars having a predetermined amplitude of movement, contact surfaces at one end of their movement, contact surfaces spaced from the other end of their movement, said second contact surfaces being 130

connected with said first contact surfaces by crossed wires.

2. An electrical switch, comprising movable switch bars, contact surfaces at one end of their movement, contact surfaces of limited area spaced from the opposite end of the movement of the switch bars and from the first contact surfaces, and crossed wires electrically connecting said first and second contact surfaces.

3. An electric switch, comprising movable switch bars having a predetermined

amplitude of movement, contact surfaces at one end of their movement, second contact surfaces spaced from the other end of their movement, the extent of said second contact surfaces being variable, said second contact surfaces being connected with said first contact surfaces by crossed wires.
